CLAIM

The ornamental design for a bottle, as shown and described.

DESCRIPTION

FIG. 1 is a front elevation of a bottle showing our new design, the rear elevation is the same;
FIG. 2 is a side elevation of the bottle, the opposite side is the same;

FIG. 3 is a top view of FIG. 1;

FIG. 4 is a bottom view of FIG. 1; and,

FIG. 5 is a perspective view of the bottle.

The broken line showing of a bottle neck is for illustrative purposes only and does not form part of the claimed design.
